EMERY A. LOCKE, OF OKMULGEE, OKLAHOMA

FLUID LIFT FOR WELLS

Application filed February 9, 1929. Serial No. 338,874.

This invention relates to fluid lifts especially adapted for use in the recovery of oil. The invention forming the subject of this application contemplates a fluid lift in which the flow of fluid through a pressure fluid motor located at the bottom of the well is utilized to bring about the operation of a plunger pump and at the same time to enter into direct lifting contact with the column of fluid above to aid in the recovery of the same, the arrangement being such that the supply of pressure fluid is augmented during the down stroke of the plunger of the pump to compensate for the temporary loss of lifting force incident to the descent of the plunger.

Another feature of the invention resides in the means by which the working parts, such as the fluid pressure motor and the pump associated therewith, may be installed and removed with a minimum of effort and loss of time.

Another object of the invention is to provide a fluid lift in which the advantages of a plunger pump are retained without the inclusion of the usual sucker rods known to be so troublesome, especially in deep wells and which, by reason of the elasticity thereof reduce materially the efficiency of the conventional pump.

Another and equally important aim of the invention is to provide a fluid lift in which the strokes of the piston are arrested yieldingly to avoid pounding and rapid wear.

Other objects and advantages will be apparent during the course of the following description.

In the accompanying drawings forming a part of this application and in which like numerals are employed to designate like parts throughout the same,

Figure 1 is a fragmentary sectional view through the improved fluid lift in initial position.

Figure 2 is a detail sectional view through a pressure fluid motor and associated elements embodied in the invention, the piston of the motor being shown at the limit of the up stroke thereof.

Figure 3 is a detail sectional view through the pressure fluid motor and associated ele-

ments, the view illustrating the position assumed by the piston carried valve on the down stroke,

Figure 4 is a horizontal sectional view taken on line 4-4 of Figure 3,

Figure 5 is a group perspective illustrating a piston and a valve mechanism carried thereby.

In the drawings wherein for the purpose of illustration is shown a preferred embodiment of the invention, the numeral 5 designates a casing located within a well and having the lower portion thereof provided with a shoe 6 set above the producing stratum in the usual manner.

A conduit or tubing 7 is located within the casing 5 and receives an inner tubing or conduit 8, the members 7 and 8 being spaced to cooperate in the formation of an annular passage 3, by which a pressure fluid, such as compressed air or gas, may be brought into use as will be described. Of course, the members 7 and 8 extend from the surface as does the casing 5 and the tubing 7 has connection with a source of pressure fluid, while the tubing 8 is connected to a flow tank.

As shown in Figure 1, the tubing 7 has connection with a coupling 9 into which the upper portion of a reduced section 10 of the tubing 7 is threaded. The lower portion of the section 10 may be bottomed in the well and is provided with suitable means, such as perforations, by which oil may enter the same.

The upper terminal portion of the section 10 is shown to be internally bevelled to form a seat for an annular bushing 11 joined with the lower portion of the inner tubing 8 and providing a means by which the working parts below are suspended from the inner tubing. The opposed contacting surfaces of the bushing 11 and the upper terminal of the section 10 are oppositely bevelled and are fit closely to provide a substantially fluid tight seal. The weight of the inner tubing 8 is ample to hold the bushing 11 seated and when it is desired to remove the working parts of the mechanism, it is a simple matter to withdraw the inner tubing together with the bushing 11 and the parts suspended therefrom.

The upper portion 12 of a cylinder 14 is shown to have direct connection with the bushing 11 so that the liquid that enters through the perforations therein may enter the tubing and be conducted to the surface as will be described.

The reduced section 10 receives and is spaced outward from the cylinder 14 and a working barrel 16 to cooperate with these parts in the formation of an annular chamber 18 for the passage of liquid from the working barrel to the perforated portion 12. In other words, the annular chamber 18 provides a means by which the liquid discharged from the working barrel may be by-passed about the cylinder 14 and then directed into the tubing for conduct to the surface.

Figure 1 illustrates that the lower portion of the working barrel is provided with a coupling 20 from which the tubular body 22 of a packing device is suspended. Suitable sealing devices, such as packing rings 24, are carried by the body 22 and have fluid tight contact with the inner wall of the reduced section 10 and provide a closure for the bottom of the annular chamber 18.

The coupling 20 is provided with a seat for a foot valve 26 of conventional or other design. Obviously, the ball of the foot valve 26 provides a means by which liquid may enter the pumping chamber of the barrel 16 during the ascent of the plunger 28 and by which the return to the well of the previously admitted liquid is prevented.

The plunger 28 may also be more or less conventional in design and is provided with the usual ball by which the flow of liquid therethrough is controlled. During the up stroke of the plunger 28, the liquid previously admitted to the upper portion of the working barrel by way of the valve in the plunger 28 is discharged through the perforations 30 and is directed into the annular passage 18 for ascent into the tubing by way of the perforated portion 12.

It may be observed that the working barrel 16 is suspended from the cylinder 14 and is rigidly connected thereto through the medium of a bushing 32, the latter having a central opening for the passage of the plunger stem or rod 34. A packing unit 134 is carried by the bushing 32 and establishes a fluid tight contact between the plunger rod 34 and the bushing 32.

As shown in Figures 1, 2, and 3 the rod 34 is provided at a point between the ends thereof with a piston 36 operating within the cylinder and adapted to be elevated from below by pressure fluid, such pressure fluid being admitted to the cylinder by way of pipes 38 welded for the full length thereof to the outer side of the cylinder and extended through the bushing 11. The upper portions of the pipes 38 are extended through the bushing 11 and are in constant communica-

cation with the annular passage 3. Thus, compressed air or gas may be directed down through the annular passage 3 and introduced into the lower portion of the cylinder 14 by way of the pipes 38, of which there may be any number desired. The inlet ends of the pipes 38 are extended above the point of settlement of scale and other matter in the chamber 3.

Figure 5 illustrates that the piston 36 is provided with an annular series of longitudinal ports 45 adaptable for the passage of a pressure fluid and being controlled by a valve plate 46. The valve plate 46 is located immediately below the piston 36 and has rigid connection with a pair of stems 48, the stems being slidable through the piston 36 and extended beyond the same.

The valve plate 46 operates between the piston 36 and a shoulder member 50, the shoulder member being secured rigidly on the rod 34 and being provided with axial openings receiving the stems 48.

The initial position of the piston 36 and the associated valve 46 is shown in Figure 1 wherein it is illustrated that the packing unit 134 is in the path of travel of and is adaptable for engagement by the lower terminals of the stems 48 so that as the piston approaches the limit of descent, the valve plate is moved to closed position to cut off the flow of pressure fluid through the ports 45. The closing of the ports 45 at the completion of the down stroke, allows the pressure fluid introduced into the lower portion of the cylinder 14 to have effective lifting engagement with the piston 36.

During the major portion of the up stroke of the piston 36, the pressure fluid will hold the valve plate 46 in closed position. However, as the completion of the up stroke is approached as suggested in Figure 2, the projecting upper terminals of the stem 48, will come into contact with the fixed abutment 60 with the result that the ports 45 are opened and the free movement of pressure fluid therethrough allowed.

Of course, the upward movement of the piston 36 is accompanied by a similar movement of the plunger 28 with the result that during such upward movement, liquid is discharged from the working barrel 16 and is directed by way of the by-pass 18 and the perforated portion 12 into the tubing for elevation to the surface.

When the valve 46 is moved to open position as suggested in Figure 2, the free flow of fluid under pressure through the piston 36 is allowed so that the piston may descend and carry with it the plunger 28. During such descent of the piston 36, the valve plate 46 will remain in open position to allow of the more or less free movement of pressure fluid into the tubing to aid in the action of the plunger 28. That is to say, the introduc-

tion of the compressed air or gas into the tubing during the down stroke of the plunger 28, compensates for the temporary loss of lifting action on the part of the plunger 5 and maintains a constant upward movement of the tubing fluid.

It is important to observe that there is a generous clearance between the piston 36 and the wall of the cylinder 14 so that the constant and uninterrupted flow of fluid under pressure through the pump and into the tubing is allowed. Thus, during the up stroke 10 of the piston 36, a limited volume of fluid under pressure is admitted through the tubing to aid in the recovery of the oil and on the down stroke a substantially greater volume of pressure fluid enters the column of ascending liquid to provide full compensation for the loss of lifting action incident to 15 the down stroke of the plunger. This arrangement also lightens the column of tubing fluid and thereby prevents the working barrel from becoming gas bound.

In Figure 1, it is illustrated that the discharge ports 30 are spaced from the upper terminal of the working barrel and are successively closed by the plunger during the up stroke thereof so that the ascent of the piston 36 and associated elements is arrested 20 yieldingly. In this manner, bumping and rapid wear on the part of the movable elements is avoided. Of course, the descent of the piston 36 and associated parts is cushioned by the limited cross sectional area of 25 the passage through the plunger 28. The rod 34 may be of a weight and length suitable to bring about the desired rate of descent of the plunger 28.

From the foregoing it will be seen that 40 the pressure fluid motor is located contiguous to and is operatively connected to the pump so that the necessity of employing sucker rods is avoided. By locating the pressure fluid motor in the bottom of the well, 45 a high degree of efficiency is attained, first because the motion transmitting losses incident to the elasticity of sucker rods is avoided and, second because the elimination of rods reduces wear on the equipment such as the 50 tubing.

In the herein disclosed fluid lift, the working parts, including the pressure fluid motor and the pumping unit associated therewith, 55 may be withdrawn along with the inner tubing without disturbing the outer tubing 7. Otherwise expressed, to withdraw those parts subject to wear, it is required merely to withdraw the single member 8 and the parts suspended therefrom.

It is to be understood that the form of invention herewith shown and described is to be taken merely as a preferred example of the same and that such minor changes in arrangement and construction of parts may be 60 made as will remain within the spirit of the

invention and the scope of what is claimed.

Having thus described the invention, what is claimed is:

1. In a fluid lift for wells, a pressure fluid motor having a reciprocating element, a pumping unit at one end of said motor and having a plunger operatively connected to said reciprocating element, there being means cooperating with said pump in the formation of a passage for liquid, said pumping unit being provided with discharge means communicating with said passage and positioned to be closed progressively by said plunger to yieldingly arrest the travel of said reciprocating element in one direction. 70

2. In a fluid lift for wells, a motor having a reciprocating element, and a pumping unit at one end of said motor and having a plunger operatively connected to said reciprocating element, said pumping unit being provided with a series of longitudinally spaced outlets progressively closed by said plunger to form a means by which the movement of the reciprocating element of said motor is arrested yieldingly. 80

3. In a fluid lift for wells, a motor having a reciprocating element, and a pumping unit at one end of said motor and having a plunger operatively connected to said reciprocating element, said pumping unit being provided with a discharge for liquid, and means cooperating with said pumping unit and said motor in the formation of a liquid passage communicating with the discharge from said pumping unit, said plunger being adapted to progressively close said discharge simultaneously with the approach of the reciprocating element of said motor to the end of travel in one direction to cushion the termination of such travel. 90

4. In a fluid lift for wells, a motor having a reciprocating element, a pumping unit arranged at one end of said motor and being provided with a working barrel having discharge means at a point spaced from one end thereof to form a cushioning chamber, said pumping unit being provided with a plunger movable in said barrel and having connection with the reciprocating element of said motor, said cushioning chamber being in the line of travel of said plunger and adapted for the reception of a fluid by which the stroke of the plunger and the reciprocating element of said pump in one direction is arrested yieldingly. 105

5. In a fluid lift for wells, a pressure fluid motor, a tubing having rigid connection with the motor, a bushing associated with the motor, and a support having a seat for engagement by said bushing, a pumping unit suspended from said motor and having operative connection therewith, and pressure fluid conduits extending through said bushing and having communication with said pressure fluid motor. 115

6. In a fluid lift for wells, inner and outer tubular members, a pressure fluid motor suspended from said inner tubular member and being provided with a bushing, the outer tubular member being provided with a seat upon which said bushing rests, a pumping unit suspended from said pressure fluid motor and having operative connection therewith, and sealing means carried by the lower portion of said pumping unit and having substantially fluid tight contact with the lower portion of said outer tubing, said pumping unit and said motor being removable freely through said outer tubing.
7. In a pressure fluid motor, a motor having a cylinder and a reciprocating element therein, a pumping unit suspended from said motor and having a fluid lifting element operatively connected to the reciprocating element of said motor, and a tubular member surrounding said motor and said pumping unit in spaced relation thereto and cooperating therewith in the formation of an annular fluid passage, said pumping unit being provided with a discharge to said annular passage, the upper portion of said tubular member and the adjacent portion of said motor being provided with cooperating sealing and seating devices constituting a closure for the upper portion of said annular passage.
8. In a fluid lift, inner and outer spaced tubular members cooperating in the formation of an annular passage, a pressure fluid motor having inlet devices communicating with said annular passage, a pumping unit suspended from said motor and spaced inward from said outer tubular member to cooperate therewith in the formation of a discharge passage, said motor being provided with means establishing communication between said discharge passage and said inner tubing.
9. In a fluid lift, inner and outer tubular members, a bushing having connection with the inner tubular member, a pressure fluid motor suspended from said bushing and being provided with a reciprocating element, a pumping unit having connection with said reciprocating element and being provided with means by which the stroke of said reciprocating element is cushioned, said outer tubing having a portion thereof extended about said pumping unit in spaced relation thereto to cooperate therewith in the formation of a discharge passage, and being provided with means forming a seat for said bushing.
10. In a fluid pressure motor, inner and outer tubular members, a bushing having connection with the inner tubular member, a pressure fluid motor suspended from said bushing and being provided with a reciprocating element, a pumping unit having connection with said reciprocating element and being provided with means by which the

stroke of said reciprocating element is cushioned, said outer tubing having a portion thereof extended about said pumping unit in spaced relation thereto to cooperate therewith in the formation of a discharge passage and being provided with means forming a seat for said bushing, said motor being provided with means establishing communication between said passage and said inner tubing.

In testimony whereof I affix my signature.

CHARLES H. BERGQUIST.
